UNITED STATES PATENT OFFICE.

HENRY STRAND, OF CLEVELAND, OHIO.

EXPANSIBLE TOOL FOR HONING CYLINDERS.

Application filed October 3, 1924. Serial No. 741,513.

To all whom it may concern:

Be it known that I, HENRY STRAND, a citizen of the United States, residing at Cleveland, in the county of Cuyahoga and State 5 of Ohio, have invented certain new and useful Improvements in Expansible Tools for Honing Cylinders, of which the following is a specification.

This invention relates to improvements in 10 expansible tools for honing cylinders of automobile engines and the like, having for an object the provision of means whereby uniform honing of a set of such cylinders may be accomplished.

15 Another object is to provide a tool of this character with a gage by means of which the expansible honing stones may be accurately adjusted, and locked at any point of adjustment.

20 A further object is to provide a tool of this character wherein the structure is such as to facilitate replacement of broken or worn out honing stones.

It is likewise an object to provide a tool 25 of this character in which the honing stones are radially adjustable through being acted upon by a pair of spaced integrally formed cones which may be adjusted and locked at any desired point.

30 Other objects will be in part obvious and in part pointed out hereinafter.

In order that the invention and its mode 35 of operation may be readily understood by persons skilled in the art, I have in the accompanying illustrative drawings, and in the following detailed description based thereon set out one possible embodiment of the same.

Figure 1 is a side elevation of a hone con- 40 structed in accordance with my invention;

Figure 2 is a similar view, one of the hone segments being moved;

Figure 3 is a vertical longitudinal section 45 of the expansion device, certain portions being shown in elevation;

Figure 4 is a detail elevation of the expansion cones;

Figure 5 is a central vertical longitudinal 50 section of one of the honing segments or stones, and

Figure 6 is a sectional view taken sub- 55 substantially on the line 6—6 of Figure 3.

Having more particular reference to the drawings throughout which similar characters of reference designate similar parts, 55 this improved expansible tool for honing cylinders may be stated as comprising a spindle 10, one end of which is threaded and designed to be detachably connected to a universal joint, (not shown) through which 60 operation of the cone is effected by means of a motor or the like power plant. Pinned or otherwise fastened to the opposite end of the spindle 10 is a spider 11 which consists of a disc-like body 12 integrally carrying a set 65 of radiating fingers 13, the function of which will be hereinafter apparent. Arranged between this spider 11 and the threaded portion of the spindle 10 is a second spider 14 which is free to move longitudinally as is clear in Figure 3 of the accompanying drawings.

This spider 14 includes a set of radiating fingers 15 and an outwardly longitudinally 70 extended neck 16, this neck and the body portion of the spider having a central opening 17 within which is slidably arranged a sleeve 18 carried by the expansion cones. Relative rotation of this sleeve and spider 75 14 is prevented through the provision of a key 19 which is carried by the spider and slides in a groove 20 formed in the sleeve 18.

The fingers 13 and 15 carried by the aforementioned spiders are designed to mount the honing segments or stones and permit radial 80 expansion thereof when an expansion member arranged upon the spindle 10 is longitudinally adjusted with respect to the other elements.

As shown in Figures 3 and 4 the sleeve 85 18 is externally threaded adjacent its outer end and is designed to threadedly engage a collar 21 which forms one portion of a gage by means of which accurate adjustment of the hone is attainable. This collar 21 is provided with a finger piece 22 which may be knurled and the neck portion provided with 90 graduations designed for co-action with a pointer or arrow (not shown) carried by the neck 16 of the slideable spider 14. In the drawings the arrangement of the graduations and arrow is shown in the reverse relation to that just set forth.

The sleeve 18 as previously stated is in-

tegrally formed with the expansion member, said member including a pair of spaced cones 23 which are inter-connected by an elongated neck portion 24. As shown in Figures 2, 3, and 5 these cones are inclined in the same relative direction and are simultaneously adjustable with rotation of an adjusting nut 25 arranged upon the threaded end of the spindle 10. The relative positioning of these expansion cones with respect to the honing segments or stones is shown in Figure 2. It is obvious that rotation of the adjusting nut 25 will move the elongated sleeve 26 longitudinally within the externally threaded sleeve 18 with the result that the cones 23 will be moved to expand the stones. In Figure 3 there is shown a coil expansion spring 27 which engages the inner end of the elongated sleeve 26 and the inner end wall of the externally threaded sleeve 18. A short ring 28 is arranged between the adjusting nut 25 and the elongated sleeve 26 so as to reduce to a minimum any tendency of said sleeve 26 to rotate during adjustment of the tool. A lock nut 29 is arranged behind the adjusting nut 25 for obvious reasons.

Each honing segment as shown in Figures 1, 2, and 5 consists of a body portion or holder 30 whose inner longitudinal surfaces are inclined to correspond with the inclination of the surfaces of the cones 23 so as to permit uniform radial adjustment over the entire length. The outer end 31 of each holder 30 is provided with a circular opening for the reception of one of the fingers 13 carried by the spider 11 which is pinned to the spindle 10.

The outer face of the holder is channeled to receive a block of carborundum or the like material, said channel opening through the other end of the holder 30. In order to prevent displacement of the block of carborundum I detachably secure to the open end of the holder 30 a bracket 32 which consists of a body portion having a circular opening 33 therethrough and a pair of oppositely directed apertured wings 34. These wings 34 are designed for alinement with threaded openings (not shown), formed in the end of the holder 30 and designed for the reception of screw fasteners 35. It is obvious that this structure permits of ready removal of the honing stones when desired. Each segment is provided at opposite ends with hooks 35 which are designed to retain coil springs 37 whose function is to yieldably hold the several segments upon the spiders 11 and 14. In using this hone, the adjusting nut 25 is rotated to expand or permit contraction of the segments to the desired diameter. At this point the locking nut 29 is turned to snugly engage the adjusting nut and prevent its backing up on the spindle 10. As a

further means for preventing a change in the adjustment of the segments and to simultaneously determine the point at which the segments must be adjusted to uniformly hone a set of cylinders I rotate the gage ring 21 upon the externally threaded sleeve 18 carried by the expansion member. It is obvious that rotation of this gage ring will tend to force the two spiders toward one another and consequently tightly grip the honing segments between the fingers 13 and 15 upon which said segments are readily slideable. At this point the operator will observe the relation of the pointer and graduations of the gage and as a result will be able to uniformly hone a set of cylinders, eliminating the necessity for comparing the measurements of several cylinders being honed. It is apparent that this gage mechanism will effectively serve as a locking device as above stated and will provide a simple means for assuring proper honing of cylinders of automobile engines and the like.

Manifestly, the construction shown is capable of considerable modification and such modification as may fall within the scope of my claims, I consider within the spirit of my invention.

I claim:

1. A honing tool comprising a spindle having one end screw threaded, a spider fixed to the other end of said spindle, radial fingers on the spider, a pair of spaced interconnected expansion cones slideable upon the spindle, a sleeve integrally formed with one of said cones and spaced from the spindle, a second finger carrying spider slideably arranged over said sleeve, honing segments radially adjustable upon the spiders, a second sleeve having one end extending into the space between the spindle and the first sleeve, an expansion coil spring in said space, a nut threaded upon the spindle to move the second sleeve and slideably adjust the cones, and means for locking the parts in any adjusted position.

2. A honing tool comprising a spindle having one end screw threaded, a spider fixed to the other end of said spindle, radial fingers on the spider, a pair of spaced interconnected expansion cones slideable upon the spindle, a sleeve integrally formed with one of said cones and spaced from the spindle, a second finger carrying spider slideably arranged over said sleeve, honing segments radially adjustable upon the spiders, a second sleeve having one end extending into the space between the spindle and the first sleeve, an expansion coil spring in said space, a nut threaded upon the spindle to move the second sleeve to slideably adjust the cones, and a combined gage and locking ring threadedly mounted upon the first named sleeve and movable into engagement with the second named spider.

3. A honing tool comprising, a spindle, a spider at one end of the spindle having radiating fingers, an expansion cone slidable on the spindle, a second finger carrying spider
5 movable longitudinally over the spindle near its other end, stone holders, apertured bracket members carried by said holders and slidable radially on the spider fingers, a member threaded on said other end of the spindle, and a coil expansion spring between 10 the cone and said member.

In testimony whereof, I affix my signature.

HENRY STRAND.
